UNITED STATES PATENT OFFICE

LOTTIE LAURIE McCALL, OF BILOXI, MISSISSIPPI

DESIGN FOR A DOLL

Application filed October 4, 1930. Serial No. 37,141. Term of patent 14 years.

To all whom it may concern:

Be it known that I, LOTTIE LAURIE McCALL, a citizen of the United States, residing at Biloxi, county of Harrison, State of Mississippi, have invented a new, original and ornamental Design for a Doll, of which the following is a specification, reference being had to the accompanying drawing, forming a part thereof.

I claim:

The ornamental design for a doll, substantially as shown.

LOTTIE LAURIE McCALL.
